(57) **CLAIM**

The ornamental design for a compact dispenser, as shown and described.

DESCRIPTION

FIG. 1 is a perspective view of the compact dispenser of the new design;

FIG. 2 is a front elevational view of the compact dispenser of FIG. ;

FIG. 3 is a left elevational view of the compact dispenser of FIG. 1;

FIG. 4 is a right elevational view of the compact dispenser of FIG. 1;

FIG. 5 is a rear elevational view of the compact dispenser of FIG. 1;

FIG. 6 is a top plan view of the compact dispenser of FIG. 1; and,

FIG. 7 is a bottom plan view of the compact dispenser of FIG. 1.

The portions of the Figures shown in broken lines are not part of the claimed design and are for illustration only. The broken line(s) which define the bounds of the claimed design form no part thereof.
